UNITED STATES PATENT OFFICE.

FRANK C. ANDERSON, OF CINCINNATI, OHIO, ASSIGNOR OF ONE-HALF TO
N. PAUL FENNER, JR., OF CINCINNATI, OHIO.

ADJUSTABLE SWITCH CONNECTION.

SPECIFICATION forming part of Letters Patent No. 726,613, dated April 28, 1903.

Application filed September 13, 1902. Serial No. 123,266. (No model.)

To all whom it may concern:

Be it known that I, FRANK C. ANDERSON, a citizen of the United States, residing at Cincinnati, in the county of Hamilton and State 5 of Ohio, have invented certain new and useful Improvements in Adjustable Switch Connections, of which the following is a full, clear, and exact description, reference being had to the accompanying drawings, forming 10 part of this specification.

My invention relates to the mechanism for adjustably connecting the point-rails of a switch to the switch-throwing bar; and it has for its object the provision of simple and 15 efficient means for effecting this adjustment, which will enable the point-rails to be adjusted independently of each other and at the same time accurately, so as to fit to the main rails and without the liability of the 20 parts becoming corroded, and whereby a very nice adjustment can be obtained, as well as one that will be perfectly secure and rigid.

The novelty of my invention will be hereinafter set forth, and specifically pointed out 25 in the claims.

In the accompanying drawings, Figure 1 is a sectional side elevation through the main rail and point-rail just above the switch-throwing bar, showing the latter and the 30 parts of my invention as applied thereto. Fig. 2 is a plan view of Fig. 1. Fig. 3 is a detail side elevation showing the parts of the switch-throwing bar disconnected from the lug-plate. Fig. 4 is a plan view of the part 35 of the switch-throwing bar shown in Fig. 3. Fig. 5 is a bottom plan view of the adjusting-plate.

The same letters of reference are used to indicate identical parts in all the figures.

40 A, Figs. 1 and 2, represents the main rail near the end of the switch-point, and B the switch-point rail adjacent thereto and resting at its base on a rail-plate C, secured to two adjacent ties, between which the switch-actuating bar D passes.

45 Riveted, as at a, to the operating-bar D is a strap-plate E, which is bent up and extends toward the rails and is parallel with the bar D, leaving a space b between the two, and 50 directly under this strap-plate is secured the lug-plate F, which is secured by bolt c and

an intermediate plate d to the point-rails, as shown.

The strap-plate E and the operating-bar D have through them longitudinal slots e f, registering with each other, as seen in Figs. 3 55 and 4, while the lug-plate F has through it simply a perforation for the passage of the connecting-bolt g.

The operating-bar D has upon its upper 60 side, between the bolt g and the rivets a, a series of perforations h, which may extend through the plate, if desired. These perforations are equidistant and are staggered in parallel rows, four of such rows being shown. 65

Between the lug-plate F and the operating-bar D is secured a plate I, which I designate the "adjusting-plate," and which has through it a transverse slot i for the passage of the bolt g and upon its under side a series of 70 downward-projecting lugs j, in this instance four in number, arranged to form a parallelogram and adapted to engage with any four of the series of perforations h in the bar D to lock the plate I, and with it the lug-plate 75 F, between the strap-plate E and operating-bar D.

The bolt G passes through the slot f in the bar D, the transverse slot i in the plate I, the perforation in the lug-plate F, and the 80 longitudinal slot e in the strap-plate E, and is held by a cap-plate k, Figs. 1 and 2, straddling the strap-plate E, and by a retaining-nut L, binding upon said cap-plate. This 85 simple manner of uniting the lug-plate ad- justably to the switch-actuating bar D is exceedingly secure, is free from liability of corrosion, and by simply loosening and removing the bolt g the lug-plate F can be ad- justed with reference to the switch-operating 90 bar D to any degree desired to cause the point-rails B to accurately fit to the main rails at all times, and in this adjustment it will sometimes occur that the plate i, in addition to its longitudinal movement on the bar D 95 will also have a transverse movement, as in- dicated by the dotted lines in Fig. 2, in order, owing to the staggering of the perforations or apertures h, to advance or retreat the lug-plate F, which carries the point-rail to the 100 precise point required.

In the foregoing simple manner and by the

simple means employed I am enabled to obtain a perfect and nice adjustment of the point-rails with reference to the main rails without exposing the adjustable connection 5 to the action of the weather, and am enabled to effect the adjustment of the parts by the simple removal and replacement of a single bolt.

It is to be observed that the plate I is some-
10 what wider than the operating-bar D, so that under all adjustments of the plate I none of the perforations H are exposed to the action of the weather, so as to receive water or snow or dirt in them, which might detract from
15 the operativeness of the device.

Having thus fully described my invention,
I claim—

1. In adjustable switch connections, the
10 combination of an operating-bar for the point-
rails, a lug-plate connected to each of said
point-rails, a strap-plate rigidly secured to
said operating-bar and overlying said lug-
20 plate, an adjusting-plate interposed between
said operating-bar and lug-plate with retain-
25 ing-pins between said two last-named plates

adapted to fit a graduated series of perforations in either of them, and a clamping-bolt uniting all of said plates and passing through longitudinal slots in the top and bottom plates and a transverse slot in the adjusting- 30 plate, whereby said adjusting-plate can have longitudinal as well as transverse movement in its adjustment, substantially as described.

2. In adjustable switch connections, the
combination of the operating-bar D provided 35 with the elongated slot f and apertures h, the
adjusting-plate I provided with a transverse
slot i and retaining-dowels j to engage the
apertures h, the lug-bar F united to the
switch-point and overlying the plate I, the 40
strap-plate E secured to the bar D and over-
lying the lug-plate F, said strap-plate being
provided with a longitudinal slot e, and the
tie-bolt g uniting the parts, substantially in
the manner and for the purpose specified. 45

FRANK C. ANDERSON.
